UNITED STATES PATENT OFFICE.

NEED KNIGHT, OF LANCASTER, SOUTH CAROLINA, ASSIGNOR TO DRAPER CORPORATION, OF HOPEDALE, MASSACHUSETTS, A CORPORATION OF MAINE.

FILLING-FORK GRID FOR LOOMS.

Application filed September 9, 1922. Serial No. 587,055.

To all whom it may concern:

Be it known that I, NEED KNIGHT, a citizen of the United States, resident of Lancaster, county of Lancaster, State of South Carolina, have invented an Improvement in Filling-Fork Grids for Looms, of which the following description, in connection with the accompanying drawing is a specification, like characters on the drawing representing like parts.

This invention relates to improvements in filling detecting mechanism for looms, and the object thereof is to provide novel means for automatically clearing the fork grid of the loom from lint, waste or other material which would tend to clog the same and prevent proper operation of the filling fork.

If, during the operation of the loom, the grid of the filling fork detecting mechanism becomes clogged by reason of accumulation of lint or waste, the filling fork may be tilted for one or more picks even though there may be an absence of filling, thus resulting in the production of a faulty weave of cloth. Heretofore brushes and fingers have been employed to clear the grid from such lint and waste. The present invention contemplates broadly the use of a movable grid adapted to remove the waste, lint, or other materials from the field of the filling fork.

More specifically, the object of the invention is to provide a rotatable grid adapted by progressive rotation to remove such matter as may accumulate upon the grid.

A further feature of the invention consists in providing the rotatable grid with means operable during the movement of the lay to rotate the grid intermittently. Means are also provided for doffing the lint, waste, or other material from the rotatable grid members after such material has passed out of the field of the filling fork.

A further object of the invention is to provide a convenient and novel means for intermittently rotating the grid.

These and other objects and features of the invention will more fully appear from the following description and the accompanying drawings, and will be particularly pointed out in the claims.

The present invention is adapted to be applied to looms of usual types and conse-

quently only so much of a loom construction is illustrated herein as is necessary to show the application of the present invention thereto.

In the drawings:

Fig. 1 is an elevation of a portion of the lay of a loom illustrating the present invention applied thereto.

Fig. 2 is a transverse vertical sectional view on line 2—2 Fig. 1 also showing the position of the filling fork in operative relation thereto.

Fig. 3 is a detail elevation of a modified form of the present invention.

Fig. 4 is an end view, partially in vertical section of the construction illustrated in Fig. 3 and,

Fig. 5 is a rear elevation of the construction shown in Fig. 3.

Inasmuch as the invention is applicable to usual types of looms only a portion of the lay of the loom which supports the grid and the filling fork which cooperates with the grid are illustrated in the accompanying drawing, together with the usual protector rod from the movement of which the rotatable members of the grid may be actuated.

The loom construction illustrated in the drawing comprises the lay 1, having mounted thereupon a shuttle-box 2 and provided with the usual reed 3, the lay being provided with a recess 4, between the end of the reed and the shuttle-box to permit the passage of the filling fork. The filling fork may be of any usual character and as conventionally illustrated herewith comprises the usual slide 5, having a bifurcated end 90 provided with a transverse shaft 6, upon which is pivotally mounted a filling fork having downwardly extended tines 7, and a horizontal looped tail 8, adapted to be engaged upon detection of absence of filling by the hook 9, upon the usual oscillating weft-hammer.

The present invention relates to the grid with which the filling fork co-operates upon the beat-up of the lay. In usual constructions the grid consists of a slotted plate or a series of bars between which the tines of the filling fork enter upon the beat-up of the lay. When a strand of filling running to the boxed shuttle crosses the grid it then 105 engages the tines 7, of the filling fork, and

tilts the filling fork so that its looped tail is out of the path of movement of the hook upon the weft hammer. In the absence of filling, the filling fork is not tilted and the weft hammer therupon engages the looped tail 8 of the filling fork, and upon its receding movement moves the filling fork slide 5, and through it actuates means to effect a change in the operation of the loom, such as the initiation of the action of the transferring mechanism, or a stoppage of the loom. Where lint or waste material accumulates on the grid, the filling fork will be actuated even though there is not an absence of filling and thereby fail to effect a change in the operation of the loom and consequently produce a fault in the weave.

In the present invention a novel form of grid is provided which has a movable member or members which preferably are rotatable and progressively move the lint or other waste material out of the path of the filling fork, such waste material being removed from the movable member or members of the grid by a suitable doffing device so that the grid is maintained clean at all times.

In the preferred construction illustrated herein, the grid comprises a series of spaced rotatable members preferably in the form of disks which are so positioned as to cooperate properly with the filling fork. The rotatable grid members desirably are actuated by a mechanism which is operated during the movement of the lay. Various means can be employed for accomplishing this purpose. Two selected forms of such means are illustrated in the accompanying drawings.

In the construction illustrated in Figs. 1 and 2, the grid comprises a series of disks 11, which are fixedly secured upon a shaft 12, and spaced apart by suitable sleeves 13. The shaft 12, is mounted in bearings in the ears 14, of a channel-shaped bracket the base 15 of which is provided with a vertical slot 16, through which passes a bolt 17, which secures the bracket to the wall 18, of the shuttle-box 2. By reason of the bolt and slot connection which secures the bracket to the shuttle-box, the grid can be adjusted upwardly or downwardly into proper cooperative relation to the filling fork.

A ratchet wheel 19, is fixedly secured upon the shaft 12, and is actuated by a suitable pawl which is operated by the movement of the protector mechanism to rotate the ratchet intermittently and thereby progressively to rotate the disks of the grid.

The pawl mechanism for rotating the grid, which is illustrated in Figs. 1 and 2, comprises a pawl 20, having a hook-shaped end 21, adapted to engage the teeth of the ratchet 19. The pawl 20, is pivotally mounted upon a stud 22, upon the upper end of an arm 23, the lower end of which is pro-

vided with a lateral extension 24, having a recess partially to embrace the usual protector rod 25 of the loom. A clamping-plate 26, secured to the lateral extension 24 of the arm 23, by suitable bolts 27, serves to secure the arm 23, rigidly to the protector rod.

The pawl 20, is provided with a downwardly-extending tail 28, and a spring 29, interposed between the tail 28 and the arm 23, serves normally to press the hooked end 21 of the pawl upon the ratchet 19.

The usual oscillation of the protector rod upon the boxing of the shuttle upon each pick of the loom, causes an oscillation of the arm 23, so that the pawl 21 is actuated successively first to ride over the teeth of the ratchet 19, and then to engage and rotate the ratchet 19 and consequently to rotate the grid. Any suitable means may be provided to prevent retrograde rotation of the ratchet. As illustrated herein, a dog is provided comprising a plate 30, which is slidably mounted on pins 31, extending upwardly from the ears 14 of the bracket which supports the grid and normally rests upon said ears. The plate 30 has a tooth which rests upon and engages the teeth of the ratchet as the latter is intermittently rotated. By reason of the rotation of the grid members which is thus effected, any lint or other waste material which adheres to the disks of the grid is carried out of the field of the tines of the filling fork.

Any suitable means may be provided for doffing the waste material from the grid members. A convenient device which is illustrated herein comprises a vertical slotted plate 32, which is supported upon one of the ears 14, of the bracket. The fingers of the slotted plate extend between the disks 11 of the grid and rest at their ends against the spacing sleeves which separate the disks. In the operation of the device the progressive rotation of the disks carries the lint and other material around until such material is engaged by the fingers of the doffing plate which strip such material from the grid, thus freeing the portions of the disk which are presented to the filling fork from anything which would be likely to interfere with the proper operation of the fork.

In Figs. 3, 4 and 5, modified mechanism is illustrated for rotating the grid. In this construction as in that shown in Fig. 3, the grid comprises a series of disks 11, which are mounted upon a shaft 12, and are spaced apart by collars 13. Likewise the shaft 12, is rotatably mounted in ears 14 of a bracket, the base 15 of which is provided with a slot 16, by means of which the bracket may be adjustably secured to the shuttle-box. A ratchet disk 19, likewise is secured to the shaft 12, and is actuated by pawl and ratchet mechanism which is oper-

ated during the movement of the lay. In this construction, however, a different form of pawl mechanism is employed.

The pawl illustrated in Figs. 3, 4 and 5, 5 comprises a plate 33, having a slot 34, which slidably and rotatably embraces the shaft 12 of the grid. A weight 35, which is secured to the plate 33, by rivets 36, is provided with a tooth 37, to engage the teeth of the ratchet 19. The end 38 of the plate 33, desirably is rounded or cam-shaped, and extends a sufficient distance beyond the shaft 12 to engage the base 15 of the supporting bracket, and limits the oscillation of the plate 33, so that 10 the weighted portion of the pawl will always be maintained well above the horizontal plane of the shaft 12, and positioned at an angle relatively thereto. A suitable dog is provided for preventing retrograde rotation of the ratchet. As illustrated herein, the same form of dog is employed as that illustrated in Figs. 1 and 2, and comprises a plate 39, which is slidably mounted upon pins 40, extending upwardly from said 15 bracket and provided with an extension or tooth 41 which rests upon the teeth of the ratchet.

A doffing plate 42, having slots to receive the disks 11 of the grid, is mounted upon 20 one of the ears 14 of the brackets, and operates in the manner heretofore described.

In the operation of the device, the forward or beat-up movement of the lay and the sudden arrest of the lay as it engages the 25 fell of the cloth causes the pivotally mounted pawl to swing about the shaft 12, so that the tooth 37 of the pawl rides over the teeth of the ratchet. The slot 34, in the plate 33 permits the pawl to drop so that the tooth 37 will engage one of the teeth of the 30 ratchet. Upon the rearward movement of the lay and its sudden arrest at the end of such rearward movement, the weighted pawl is swung by its 35 momentum about the axis of the shaft 12, thus causing a rotation of the ratchet 19, and consequently rotating the grid. The swinging movement of the pawl is arrested by the engagement of the end 38 of the plate 40 33, with the bracket, and such engagement also serves to lift the pawl so that its tooth 37, is removed from engagement with the ratchet, and the pawl is ready to be again 45 swung forward upon the next beat-up movement of the lay. In this construction as in the other the lint and waste material which adheres to the disks of the grid is carried out of the field of the filling fork and removed from the disks by the doffing plate 50 42.

It will be understood that the embodiment of the invention disclosed herein is of an illustrative character and is not restrictive, and that various changes in form, construction and arrangement of parts may be 55

made within the spirit and scope of the following claims.

Having thus described my invention, what I claim as new, and desire to secure by Letters Patent is:

1. Filling detecting mechanism for looms comprising a filling fork, a grid carried by the lay comprising a plurality of movable members positioned to cooperate with said filling fork upon the beat-up of the lay, 70 means for actuating said movable member to clear the grid of lint and other materials which would prevent a proper operation of the filling fork.

2. Filling detecting mechanism for looms comprising a filling fork, a grid carried by the lay comprising a plurality of rotatable disks positioned to cooperate with said filling fork upon the beat-up of the lay, means for rotating said disks intermittently, and 80 means for doffing lint and other materials from said grid.

3. Filling detecting mechanism for looms comprising a filling fork, a rotatable grid comprising a shaft, a series of separated 90 disks secured thereto in position to cooperate with said filling fork upon the beat-up of the lay, means including pawl and ratchet mechanism for rotating said disks intermittently, and means for doffing lint and other 95 materials from said disks.

4. Filling detecting mechanism for looms comprising a filling fork, a rotatable grid carried by the lay positioned to cooperate with said filling fork upon the beat-up of 100 the lay, means for rotating said grid and a doffing device located out of the field of action of the filling fork acting to clear said grid as it is progressively rotated.

5. Filling detecting mechanism for looms comprising a filling fork, a rotatable grid carried by the lay positioned to cooperate with said filling fork upon the beat-up of 105 the lay, means for rotating said grid and means for doffing the material which adheres to the grid consisting of a plate having slots to receive the rotatable members of the grid.

6. Filling detecting mechanism for looms comprising a filling fork, a bracket adjustably secured to the lay, a shaft rotatably mounted in said bracket, a plurality of disks secured to said shaft in cooperative relation to the filling fork upon the beat-up of the lay, a ratchet secured to said shaft, 115 a pawl operable during the movement of the lay to engage said ratchet and rotate said disks intermittently, and a doffing device located out of the field of action of said filling fork acting to clear said grid as it is 120 progressively rotated.

7. In a loom comprising a lay and protector mechanism including an oscillatory protector rod, filling fork detecting mechanism including a filling fork, a rotatable 130

grid mounted on the lay and positioned to cooperate with said filling fork upon the beat-up of the lay, a ratchet connected to said grid, a pawl connected to and operable by the oscillation of said protector rod to engage the teeth of said ratchet and rotate said grid, and means for doffing lint and other material from said grid.

8. A rotatable filling fork grid and means

for clearing the same of lint and other material during its rotation.

9. A rotatable filling fork grid comprising a series of spaced disks and a doffing plate having a series of slots receive said disks.

In testimony whereof, I have signed my name to this specification.

NEED KNIGHT.
